signor to Mabs, Inc., Los Angeles, Calif., a corporation of California

Application November 6, 1947, Serial No. 142,338

Term of patent 14 years

(Cl. D92—1)

To all whom it may concern:

Be it known that I, Robert E. Minger, a citizen of the United States, residing at Manhattan Beach, county of Los Angeles, and State of California, have invented a new, original, and ornamental Design for a Textile Fabric or similar article, of which the following is a specification, reference being had to the accompanying drawing, forming part thereof.

The figure is a plan view of a piece of textile fabric, or similar article embodying my new design, a design unit of which is contained between the dash lines, such unit being repeated as indicated.

I claim:

The ornamental design for a textile fabric or similar article, substantially as shown and described.

ROBERT E. MINGER.
